UNITED STATES PATENT OFFICE.

JULIUS BJORNIE, OF WATERTOWN, SOUTH DAKOTA, ASSIGNOR OF ONE-HALF TO
THORWALD BJORNIE, OF MADISON, MINNESOTA.

DESIGN FOR A TIRE-TOOL.

52,601.

Specification for Design.

Patented Oct. 29, 1918.

Application filed July 5, 1918. Serial No. 243,486. Term of patent 3½ years.

To all whom it may concern:

Be it known that I, JULIUS BJORNIE, a citizen of the United States, residing at Watertown, in the county of Codington and State of South Dakota, have invented a new, original, and ornamental Design for a Tire-Tool, of which the following is a specification, reference being had to the accompanying drawing, forming part thereof.

Figure 1 is a side elevation of a tire tool showing my new design;

Fig. 2 is a front elevation of the same; and

Fig. 3 is a rear elevation of the same.

I claim:

The ornamental design for a tire tool, as shown.

JULIUS BJORNIE.
